Primary Examiner — Ricky Pham(74) *Attorney, Agent, or Firm* — Taylor J. Ross(57) **CLAIM**

The ornamental design for a kitchen appliance base, as shown and described.

DESCRIPTION

This application is related to co-pending application Ser. Nos. 14/071,624 and 29/471,646, which are incorporated by reference herein.

FIG. 1 is a top, front and left side perspective view of a kitchen appliance base showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view, the left side being a mirror image thereof; and,

FIG. 7 is a cross-sectional view taken along line 7-7 of FIG. 4. The broken lines shown in the drawings are for illustrative purposes only and form no part of the claimed design.
